(57) **CLAIM**

The ornamental design for a combination ceiling fan and light fixture, as shown and described.

DESCRIPTION

FIG. 1 is a perspective view from below of a combination ceiling fan and light fixture in accordance with my design; FIG. 2 is an enlarged perspective view from below of the combination ceiling fan and light fixture in accordance with my design;

FIG. 3 is a reduced bottom plan view of the combination ceiling fan and light fixture in accordance with my design; FIG. 4 is a reduced top plan view of the combination ceiling fan and light fixture in accordance with my design; and, FIG. 5 is a front elevation view of the combination ceiling fan and light fixture in accordance with my design.

The broken lines showing environmental structure are for illustrative purposes and form no part of the claimed design. In FIG. 2, the fan blades are shown broken away to indicate indeterminate length.
